FOOTBALL SHOULDER PAD

Hugo Goldsmith, Cincinnati, Ohio, assignor to
Sport Products, Inc., Cincinnati, Ohio, a corporation of Ohio

Application December 28, 1950, Serial No. 203,052

2 Claims. (Cl. 2-2)

1

This invention relates to protective armor for football players and is particularly concerned with an improved pad for protecting the shoulders, neck and upper chest of the player.

Shoulder and neck pads are conventionally constructed in pairs of identical units, one unit being fitted on each side and the pair being joined together centrally, usually by lacing in front only or in front and in back. One simple and yet very practical type of construction includes the principal elements of a pair of body members of identical construction joined together centrally in reverse position to provide the neck opening, and a pair of cap members or epaulets, one of which is joined to each body member and extends outwardly therefrom on a hinged connection. Rigid fibre sheets molded to the desired form have been the preferred material for both the body members and the cap members, and the hinged connection has usually been a leather or elastic web.

In effecting the assembly just described, the principal difficulty has been to provide a hinge which meets all of the necessary requirements. First of all, it is essential that the cap members pivot upwardly on the body members to a substantial degree in order not to hamper the upward movement of the player's arms in throwing and catching forward passes and raising the arms for other purposes incident to the game. It is also essential that this upward pivotal movement be on a relatively fixed hinge so that the cap members will not "creep" or be forced inwardly toward the player's neck. Finally and most important, it is essential that the hinge be so constructed and affixed as to almost completely prevent sidewise movement or skewing of the cap members with respect to the body members. If such skewing occurs, it will frequently happen that the cap member will be displaced from the shoulder joint which it is intended to protect and resultant injury to the player becomes probable. Since the rules of football and the player's comfort prohibit the use of metal plates in the hinge construction, it has been a continually existing problem to effect a satisfactory hinge from soft material such as leather, elastic or the like which will not be subject to one or more of the objections mentioned.

The present invention contemplates a simple expedient for the solution of this problem predicated on the concept that lateral movement of the cap member can be almost completely avoided without impairing the upward movement provided the hinge is positioned and secured in such a

2

way as to substantially eliminate all slack between the points of securance and provided further that the points of securance are spaced apart transversely to the maximum degree permitted by the width of the hinge.

One of the particular objects of the invention, therefore, has been to provide a shoulder pad construction in which the cap members are free to move upwardly and downwardly with respect to the body members but one in which sidewise movement or skewing is almost completely prevented.

Another object has been to provide a hinge construction between the body member and cap member of a football shoulder pad in which sidewise movement of the cap member with respect to the body member is substantially prevented by the elimination of a large part of the slack normally present in a leather or fabric hinge construction and one in which the sidewise movement is further restrained by the positioning of the hinge attachment member at the extreme transverse end of the hinge.

A further object has been to improve the efficiency of a hinge of the character under consideration by utilizing the body of the hinge as a cushioning element between the body member and cap member, thereby accomplishing the dual purpose of eliminating hinge slack and providing a cushion or shock absorber at the movable joint between the members.

Other and further objects and advantages will be apparent from the further and more detailed description of the invention when considered in conjunction with the drawings in which:

Figure 1 is a front elevation of a complete shoulder pad assembly representing a preferred embodiment of the invention.

Figure 2 is a plan view of one body member and cap member unit with the cap member in extended position.

Figure 3 is a similar plan view of the same unit showing the cap member in elevated position.

Figure 4 is a fragmentary end view of a cap member and body member unit showing the cap member in elevated position.

Figure 5 is a sectional view along the line 5-5, Figure 2.

Referring again to the drawings and the preferred embodiment of the invention therein disclosed, inasmuch as the two sides of the construction of the unit 10 are identical except for a reversal of positioning, the description will be limited to the right side of the construction as illustrated in Figure 1. As shown, this comprises

a body member 11 configurated as shown and preferably formed from rigid fibre material. For purposes of comfort, the inside of this member may be lined with padding 12. The cap member 13 preferably has an outer sheeting of fibre 14 and similar inner padding 15. The padding may be secured to the fibre by the stitching 16. An embossed section 17 may be formed in the outer surface of the cap member to provide a better fit with the point of the shoulder and to increase the rigidity of the construction.

A tab 18 is preferably secured to the front face of the body member by rivets 19. Loops 20 may be formed on the inner edge of the tab for the insertion of a lacing 21. A similar tab 22 is secured to the rear surface of the body member and has eyelets 23 formed therein also for the reception of a lace which is not shown. When the pad is worn, it is adapted to be laced both in front and in back and to assume the approximate position shown in Figure 1.

The essence of the present invention resides in the hinge 24 providing the connection between the cap member 13 and the body member 11. This hinge is preferably formed from one or possibly more sheets of leather, fabric or the like and includes a generally elongated rectangular body portion 25 which is adapted to be disposed on the upper surface of the cap member 13 and a pair of inwardly extending tabs 26 which are adapted to be secured to the upper surface of the body member and to occupy a cushioning position between the body member and the cap member when the latter is in extended position in the manner illustrated generally in Figure 5.

It is an essential feature of the invention that the hinge be folded downwardly around the inner edge of the cap so that the side of the hinge which is exposed in the cap attachment becomes the concealed side in the body member attachment and so that the two points of attachment are in substantial vertical alignment as illustrated best in Figure 5. Rivets 27 and 28 comprise the preferred attaching means in both cases, although it will be obvious, of course, that other means of attachment may be provided if desired. As best shown in Figure 5 when the cap member 13 is in the extended position, hinge 24 assumes a U-like configuration, being secured to the upper portion of cap 13, folded back over the inner edge of the cap, and secured to the outer, or exposed, surface of body member 11. Inward movement, or skewing, of cap 13 is prevented by the constraint of the inner edge of the cap within the closed portion of the U. Fore and aft movement is prevented by the tautness of the hinge sheet, leaving no excess material to permit play.

In the preferred attachment of the hinge to the cap member as illustrated particularly in Figures 2 and 4, the rivets 27 or other attaching means are preferably located closely adjacent the inner edge of the cap member. Similarly as illustrated particularly in Figures 3 and 4, the rivets joining the tabs 26 to the body member are positioned as close to the edge of the cap member as is practicable. It is also essential to the invention that the attachment means 27 be closely adjacent the outer ends of the body member 25 and that the attachment means 28 be closely adjacent the outer ends of the tabs 26. By virtue of this construction and arrangement, the maximum amount of slack which would otherwise be present in a hinge of this type is eliminated, first by

insertion of the hinge member between the body and cap, and second by the positioning of the attachment means. The positioning of the hinge between the body member and cap member not only assists in the elimination of slack, but also provides a cushioning joint which effects a smoother hinge movement.

While the invention is, of course, a simple one, the construction which is provided effectively eliminates the objectionable skewing of the cap members and thereby increases the degree of protection afforded to the shoulder joint and collarbone. The construction is inherently strong and rugged and fully resistant to all normal shocks and blows.

Having fully described my invention, I claim:

1. A football shoulder pad construction including a pair of arcuate body protecting members encircling the neck of the wearer, said members including a top portion coinciding with the center of the arc along which said members are configurated, a pair of cap members, extending outwardly from said body members to protect the shoulder joints, hinge means for mounting the cap members to the body members, said hinge means including a flat sheet of foldable material, said sheet assuming a U-like configuration when said cap member is in the extended position, one edge of said sheet being secured to the upper surface of the cap member, the sheet being folded back over the inner edge of the cap and being directly secured to the outer surface of the body protective member on the top portion thereof, the points of securance of said sheet member to said cap and said body member being in substantial vertical alignment adjacent the inner edges of said cap, whereby the amount of hinge free material is minimized.

2. In a football shoulder pad construction including a pair of arcuate neck and upper body protective members encircling the neck of the wearer, said members including a top portion coinciding substantially with the center of the arc along which said members are configurated, a pair of cap members for protecting the shoulder joints, one of said cap members extending outwardly from each body member, hinges for mounting the cap members upon the body members, each of said hinges comprising flexible flat sheet material, said sheet material being secured to the upper surface of a cap member, the points of securance of said sheet material to said cap member being disposed closely adjacent the inner edge of said cap member, said sheet material including two tab portions, said tab portions being wrapped around said inner edge of the cap member, extended outwardly, and secured directly to the upper surface of a body member on the top portion thereof, the two tab portions of said sheet material being secured to the body member at points adjacent to one another, the points of securance of said sheet material to said cap and said body member being in substantial vertical alignment adjacent the inner edge of said cap, said tab portions of said sheet material being interposed in the joint by the body member and cap member.

HUGO GOLDSMITH.
